UNITED STATES PATENT OFFICE.

EDMUND S. CHURCH, OF DAYTON, OHIO, ASSIGNOR TO THE NATIONAL CASH REGISTER COMPANY, OF DAYTON, OHIO, A CORPORATION OF OHIO, (INCORPORATED IN 1903.)

TIME-PRINTER.

1,087,215.

Specification of Letters Patent. Patented Feb. 17, 1914.

Application filed December 11, 1908. Serial No. 467,073.

To all whom it may concern:

Be it known that I, EDMUND S. CHURCH, a citizen of the United States, residing at Dayton, in the county of Montgomery and 5 State of Ohio, have invented certain new and useful Improvements in Time-Printers, of which I declare the following to be a full, clear, and exact description.

This Invention relates to improvements in 10 time printers, more especially to those which are arranged to operate in connection with other machines such as cash registers.

An important consideration in the combination of a time printer and cash register 15 is that the clock mechanism should be as independent as possible from vibrations of the printing mechanism or other moving parts of the cash register. It is therefore among the objects of this invention to attain 20 such desired relation between the two co-acting devices.

A few undesirable features found to a considerable extent in time printers and which are among the objects of this invention to avoid are, that the type-carrying elements are driven directly by the clock mechanism or instead corresponding elements are driven by the clock mechanism, which elements control devices for positioning the 30 type-wheels according to the setting of the elements which are positioned by the clock mechanism, but if neither of these arrangements is employed the clock mechanism sometimes merely controls separate driving 35 mechanism for the type-wheels. The first two have the disadvantage that the clock mechanism is burdened with the work of positioning the type-wheels or corresponding elements, making it difficult to regulate 40 the clock when standard clock mechanisms are employed and the clock mechanism is also liable to harm, through the jarring or vibration of the same when an impression is taken from the type-wheels because of the 45 direct connection between the type-wheels and the clock. The last arrangement while an improvement over the first two, still more or less connects the clock mechanism with the type-wheels. This arrangement is somewhat 50 objectionable, inasmuch as clock mechanisms are very delicate and have very little surplus power, so that any additional work, and especially any intermittent work requiring a variable amount of energy, is

liable to impair the accuracy of the clock. 55 The best solution of the problem consists in giving the clock practically nothing to do besides moving its own mechanism, and this is accomplished in the present invention by having the type-wheels wholly independent 60 of the clock mechanism and the setting of the type-wheels is accomplished by devices which co-act with elements which are separately driven free from the clock mechanism and the clock mechanism serves to control 65 the driving means for the setting elements.

In one type of time printer which is described in the co-pending application of F. K. Fassett, Serial No. 341,101 the devices for setting the type-wheels are arranged so 70 that when an impression is made, they will move forward and co-act with stepped cams which are positioned by the clock mechanism. These devices are arranged in pairs, which co-act with pairs of oppositely 75 stepped cams, so that if one device or slide of a pair is stopped by its respective cam at a certain position, the other slide will engage its respective cam and come to rest after traveling an extent which is in inverse ratio to the extent of movement of the first mentioned slide. One of the slides is provided with a rack meshing with a pinion which is connected to the respective type-wheel for said pair of slides. The object of 80 the above described mechanism is to obtain the differential setting of the type-wheels by means of an invariable stroke of the moving part which carries the pairs of slides and also in the present invention, the prime object of the stepped cams and the pairs of 85 co-acting slides is for the purpose of converting an invariable movement of one part of the machine into a differential movement which may be employed to rotate the printing wheels desired extents. 90 95

In the present machine, the same principle of attaining the differential setting of the type-wheels is employed but in a simpler form, namely, each pair of slides are provided with rack teeth and are connected by a pinion meshing with said teeth and one slide is provided with a set of rack teeth which mesh with a pinion rigid with its respective type-wheel, the same as is described in the before-mentioned patent application, but only one of said slides is arranged to co-act with a stepped disk and 100 105

only one of said disks is necessary for each pair of slides. The arrangement is such that the connecting pinion between the two slides is given a constant movement each time a printing is made, the pinion carrying with it the two slides but when one of the slides engages a stepped cam further movement of the pinion will cause the pinion to roll along the rack of said slide and the arrangement is such that it will then move the companion slide in inverse ratio to the extent of movement of the slide which engages the stepped disk. Therefore, the slides are moved differently while the sum of the movements of the two slides is always constant. It may thus be seen that by means of this mechanism a constant invariable movement may be converted into a desired differential setting and the desired result is attained by the use of merely one stepped disk to each pair of slides.

Another important feature of this invention is that the slides which engage the stepped disks of the higher denominational orders are made in two parts, the part which actually engages the disk being hinged to the other part of the slide and means are employed for rocking the hinged portion of the slide at the proper time so that when the slide is moved it will engage a desired stop of the stepped disk, regardless of the rotation of the disk. This construction of the slide as applied to the construction shown in the drawings is principally a safety device, for instance, one such slide is used in conjunction with the hours disk and a cam which is rotatable with the minute disk causes the hinged portion of the slide to rock when the minutes disk passes from the fifty-nine minute position to the zero position, thus insuring that if an impression were taken at this moment when the minutes disk passes from fifty-nine to zero that the hours type-wheel will be moved one step in advance. Without this safety device if the hours disk does not rotate in very exact relation with the minutes disk, through too little or too much clearance between the hours plunger and the receding step on the hours disk, there is danger of having impressions which are made at the even hours indicating one hour earlier or later than the correct time. A similar safety device serves to insure the proper movement of the meridian plunger at noon or midnight.

With these and incidental objects in view, the invention consists in certain novel features of construction and combinations of parts, the essential elements of which are set forth in appended claims, and a preferred form of embodiment of which is hereinafter described with reference to the drawings which accompany and form part of the specification.

Of said drawings:—Figure 1 is a front elevation of a time printer constructed according to this invention with the protecting casing for the same removed. Fig. 2 is a side elevation of the same but also indicates the cash register and the connecting mechanism between the two devices. Fig. 3 is a development of a section taken on line 3—3 of Fig. 1. Fig. 4 is a side elevation of the pairs of slides for setting the type-wheels. Fig. 5 is a rear elevation of the same. Fig. 6 is a rear view of the safety device for operating upon the hour and meridian plungers. Fig. 7 is a sectional view taken on the line 7—7 Fig. 4. Fig. 8 is a diagrammatic view of the rear supporting plate for the clock mechanism, and indicates the centers of the various shafts of the clock mechanism, also the escapement pawl which is operated by the clock mechanism. Fig. 9 is a rear assembled view of the various stepped disks. Fig. 10 is a detail of the minutes disk. Fig. 11 is a detail of the tens-of-minutes disk. Fig. 12 is a detail of the hours disk, and, Fig. 13 is a detail of the meridian disk.

The chief end of this invention is to provide an accurate and reliable device for causing the ordinary printers of cash registers to print the time at which transactions are made, besides the date and amount of the transaction.

The means for setting the type-wheels which are controlled by the cash register are not shown in the drawings, but the type-wheels themselves and the pinions to which they are sleeved are indicated in Fig. 1.

The invention is intended particularly to be applied to machines of the type shown in the patent to Cleal and Reinhard, No. 580,378, April 18, 1897, as improved by the patent to Carroll No. 754,049, March 8, 1904. These patents show a machine of the so-called two motion type in which a handle is employed to furnish the power for the main operating mechanism and in the present case the handle driven devices are arranged to position the type wheels under control of certain graduated elements. It will be evident, however, that the invention is complete in itself aside from the particular means for positioning the type wheels and therefore may be applied with equal success to many other types of registers besides that described in the cited patents. In fact the mechanism may be used as a time stamp alone and without connection to a cash register or other accounting machine, in which case a hand lever or other moving part may be used to operate the mechanism.

Briefly stated the general principle of the construction shown in the drawings is as follows: The clock mechanism serves the purpose of merely rocking an escapement pawl which co-acts with an escapement

wheel driven by a coiled spring entirely independently of the clock mechanism. The clock mechanism, therefore, merely serves to regulate the rotation of the separately driven escapement wheel. The escapement wheel is so geared to various stepped disks that the minutes disk will move one step each minute, the tens of minutes one step for each ten minutes, and the hours disk one step for each hour, and the meridian disk one step for each twelve hours. A series of plungers are located in alignment with said disks and when printings are made the plungers are moved toward the disks and are stopped at positions determined by the particular steps of the disks which are in their paths. The plungers are moved upwardly by means of a shaft which extends across all of the plungers and which is given an invariable reciprocation at each operation of the machine. This shaft is connected to each plunger by pinions which are journaled on the shaft and mesh with rack teeth cut in the plungers. Spring resistance is provided normally to prevent rotation of the pinions, but when the plungers have engaged their respective stepped cams or disks, further movement of the aforesaid reciprocating shaft forces the pinions to rotate upon the racks of the plungers until the shaft reaches the end of its stroke. A companion rack members is provided for each of the plungers and meshes with the same pinion but will be moved extents which are in an inverse ratio to the extents of movement of the plungers, through means of the rotation of the intermediate pinions after the plunger slides have engaged their respective disks. The companion slides mesh with other pinions which are rigid with type-wheels carrying type for printing the minutes, tens of minutes, etc., according to which of the stepped disks its respective slide is connected. These type-wheels are mounted at the side of the ordinary amount type-wheels of the cash register, so that when the impression platen is operated a printing of the time will appear at the side of the slip or check upon which the amount is printed.

As the positioning of the stepped disks is automatically taken care of by the clock mechanism and the mechanism for rotating the said disks, all that is necessary in order to obtain a printing of the time is to move the shaft which carries the connecting pinions for the pairs of slides toward the stepped cams a certain invariable distance, so that the plungers which are moved by the said pinions co-act with the stepped disks in a way to effect the desired setting of the type-wheels. The platen is then forced against the type-wheels and the desired impression is obtained.

Having reference to the drawings, the mechanism of the machine is arranged as

follows: Both of the springs 20 and 33 (Figs. 2 and 3) for respectively driving the clock mechanism and the stepped disks are wound from the key shaft 15 which carries a pinion 16 meshing with a gear 17 on the shaft 19 to which the inner ends of the springs 20 and 33 are secured. The gear 17 carries the usual ratchet 14 and pawl for preventing backward rotation of the springs.

The clock spring 20 as shown in Fig. 2 rotates the ordinary clock gearing which is merely indicated in said figure by the gear 21, pinion 22 and gears 23 and 23' which last are located between the end plates 24 and 25 which inclose the clock mechanism including the hair spring with its escapement pawl and escapement wheel, etc., as is usual in clocks and is therefore not illustrated in detail; but a shaft 26 of the clock mechanism which makes one rotation during each two minutes is shown provided with an eccentric pin 27 which operates in a slot 28 Fig. 8 in a lever 29 which is securely fastened at its upper pivoted end to an escapement pawl 30, (Fig. 9). Said pawl co-acts with an escapement wheel 31 to allow the same to move one-half of a tooth space each minute, and as the escapement wheel has thirty teeth it will make one revolution per hour. The escapement wheel is urged to rotate in the direction indicated by the arrow 32, Fig. 9, by the coiled spring 33 (Fig. 2) which through the toothed drum to which one end of the spring is secured, drives the pinion 18 which is rigid on the same shaft with a gear 34 and the gear 34 meshes with a pinion 35 on a shaft 36 which shaft also carries a pinion or gear 37 (Fig. 3) which meshes with a gear 38, the gear 38 being secured to the escapement wheel 31. By following out the gearing so far indicated it may be seen how escapement wheel 31 is rotated under the action of the spring 33, the rate of rotation of the escapement wheel being controlled by the escapement pawl 29 which is rocked by the clock mechanism driven by the spring 20. The gear 38 is secured to a ratchet wheel 39 which is connected to the minutes disk 40 by the pawl 41 which is mounted upon the minutes disk. The pawl and ratchet connection between the minutes disk 40 and the escapement wheel 31 allows the minutes disk to be rotated in a forward direction independently of the escapement wheel so that the same may be set by rotation of the minutes pointer 42 which is rigidly secured by a thumb nut 43 to the shaft 44 upon which shaft the minutes disk is rigidly secured. The minutes disk is of course so geared to the hours and meridian disks that rotation of the same either through the escapement 31 or the thumb nut 43 will effect the correct corresponding rotation of the disks of higher order and also of the hours pointer 45 which is secured to

the sleeve 46 surrounding the shaft 44 and upon which sleeve the hours disk 47 is rigidly mounted. The tens of minutes disk 48 is rigidly secured to the minutes disk 40 it being unnecessary to gear the two disks together as the steps upon the same are so arranged that for each travel of ten steps of the minutes disk the tens-of-minutes disk will travel one step; the steps of course being proportioned in length. The pinion 50 is secured to the minutes and tens of minutes disks so as to rotate therewith and meshes with a gear 51 which is fixed to a sleeve 52 upon which is mounted a pinion 53 which pinion meshes with a gear 54 which is rigid with the hours disk 47 and this arrangement of gears affords movement of the hours disk one step for each complete rotation of the minutes and tens of minutes disks. The hours disk is in turn geared to the meridian disk 121, to effect the movement of the same one step for each revolution of the hours disk, through the gear 55 which is rigid with the hours disk, and gear 56 which is mounted upon the sleeve 57, which sleeve carries a pinion 58 meshing, through the intermediate pinions 60 and 61, with the gear 59 which is rigid with the meridian disk. (Figs. 1 and 3).

From the foregoing description it will be evident that the clock mechanism is limited in function to a control of the stepped disks or graduated elements, and has almost no external work to perform. The energy required to vibrate the escapement lever 29 and escapement pallet 30 is very small, and the power for turning the graduated elements or stepped disks is derived from an independent spring so that accuracy of the clock mechanism is assured. The stepped disks are all connected together by trains of gearing so that only the minute disk is driven directly from its spring, the other disks being geared in a manner somewhat analogous to that used for driving the ordinary hour hand of a clock from the minutes disk. It will be evident that these disks instead of being stepped might be uniformly circular and provided with printing type, but this construction would be open to the objection previously stated, that the clock is liable to derangement by the blow of the printing hammer. To obviate this difficulty the stepped disks are used merely to position other elements which themselves control the movement of the printing devices, these elements being movable at each operation of the mechanism from a certain normal position to differential positions depending on the momentary position of the graduated elements.

The shaft 65, (see Fig. 2) upon which the driving gears or pinions 67 are journaled is carried by a pair of slides 68 and 69 which are pivotally hung from a bell-crank lever

70 pivoted to the side-frame of the machine at 71. The upwardly extending arm of the bell-crank lever carries a roller 72 which contacts with a groove 73 in a cam disk 74 which is mounted upon a stub-shaft 75. The stub-shaft 75 carries a large gear 76 which meshes with a small pinion 77 rigidly mounted upon the main drive shaft 78 of the machine, and which is given two rotations upon each operation of the machine, thereby causing the gear 76 to make one-half of a rotation and the groove 73 in the cam 4 is therefore oppositely cut on each side of a center line through the cam so that at every complete operation of the machine, the bell-crank will 75 be rocked forward and backward.

The gear mechanism, referred to, may be of any desired form, that shown being substantially like the mechanism of Fig. 9 of the Carroll Patent No. 754,049, cited, in 85 which the gear 99 thereof has the same function and general position as the gear 76 in the present case.

The bell-crank carries with it the slides 68 and 69 through which the shaft 65 extends and the upward movement of the pinions 67 which are carried by the shaft 65 therefore both causes and permits the plunger slides 80, 81, 82 and 83 to rise assisted by the action of the springs 90 connected to 95 said slides until the plungers engage their respective stepped disks. During the upward movement of the plungers, the pinions 67 (each of the pinions 67 are made of two segmental halves 84 and 85 of different radii 100 for the convenience of arrangement of related mechanism) roll upon the plunger companion slide racks 87 and therefore do not alter the position of the slide racks 87 but after the plungers engage their respective disks further upward movement of the shaft 65 will cause the pinions 67 to rotate upon the racks carried by the plunger slides until the supports 68 and 69 for the same reach the end of their stroke. As 110 stated above, the pinions 67 are made of two segment-halves 84 and 85 the last of greater diameter than the other; therefore, the peripheral movement of the one side 85 of the pinion will be greater than the peripheral 115 movement of the other side of the pinion and as the diameter of the segment-halves are in the ratio of two to one, the movement of the plunger slides is stepped up to twice the amount at the type-wheels, thus permitting the use of large type on the type-wheels and also making any back-lash between the segment gears and the racks less evident in the alinement of the type-wheels. The two halves of each pinion are pinned together as 120 indicated at 86. When the pinions 67 rotate after their respective plunger slides have come to rest, the pinions cause a corresponding movement of their respective racks 87 which mesh with pinions 88 sleeved 125

to the type-wheels 89, and rotate the type-wheels according to the extent of rotation of the pinions.

- The operation of the differential mechanism just described is as follows: When the slides 68 and 69 are moved upwardly the pinions 67 carry with them their respective plunger slides 80, 81, 82 and 83 which are aided by the springs 90 until the plunger slides engage the stops of the stepped disks which are in their paths, the pinions 67 meantime merely rolling upon the rack slides 87; but after the plungers have engaged the stepped disks, the further movements of the pinions 67 in a vertical direction will cause the same to roll upon the plunger slides and therefore lift their respective rack slides 87 and cause the same to rotate the respective type-wheels to which they are connected, an extent which is in proportion to the distance between the point where their respective plunger slides were stopped by the stepped disks and the end of the stroke of the slides 68 and 69. The stops on the stepped disks are arranged so that the stroke of the plungers from normal position may be divided as follows, that of the minutes plunger slide 80 may be limited to any one of nine different parts of the full stroke, likewise plunger slide 81 for the tens of minutes disk may be limited to any one of five parts of its full stroke, plunger slide 82 to any one of eleven parts of its full stroke and plunger slide 83 to merely its initial position or the entire stroke of the same. The springs 90 may be omitted from the construction shown as the differential mechanism is positive in its operation, and not dependent upon springs 90.
- For convenience and accuracy of operation the stepped disks are all positively geared together, as before described, thus contributing to simplicity of construction and accuracy of movement. It will be clear, however, that the disks of higher orders, that is, the hour and meridian disks move very slowly, the hours disks being given a complete rotation in twelve hours and the meridian disk a complete rotation in twenty-four hours so that the movement in any one minute of these two disks of higher order will be very small. The result would be that it would be impossible to make the parts accurately enough to provide for unerring setting of the hours and meridian printing wheels from such slow moving graduated elements and that under some conditions a very slight amount of wearing would cause the hours and meridian type-wheels to be set inaccurately due to a very little back lash in the connecting mechanism for the corresponding graduated elements or to any slight wear thereof. The construction shown including the positive gearing between the separate orders of graduated

elements is of great value, but in order to render it certain in its operation of accurately positioning the type wheels, some additional controlling device for the plungers of higher order should be employed in order that no small amount of wear or back lash should disturb the accuracy of the mechanism. With this object in view a construction is employed under the control of the minutes graduated element 47, such that the plungers for the higher order elements, that is, the hours and meridian disks are shifted in the plane of movement of those disks at the end of each hour, thereby causing them to be obstructed by the succeeding step of the graduated elements without fail. During nearly all of the hour, the higher order plungers move slowly in one direction, thereby more or less keeping pace with the graduated elements of higher order, but precisely at the end of each hour, the plungers are permitted to reverse their shifting movement to a position such that they will unerringly engage the succeeding step of the higher order graduated elements.

A snail cam 92 (see Figs. 6, 9, 2, and 3) rotates with the minutes and tens of minutes disks 40 and 48 and is arranged so that the cut-away part 93 of the same will arrive at the top of a pivoted lever 94 when the disks 40 and 48 have made a complete revolution to their zero position, when the lever 94 will rock upon its shaft 95 under the action of the spring 96, and the pin 97 which is carried by an arm 98 rigid on the shaft 95 with the lever 94, will rock out of engagement with a pair of pivoted arms 99 and 100 carried by the hours plunger slide 82 and the meridian plunger slide 83 so that the said levers 99 and 100 will be rocked by their springs 101 clear of the points 102 and 103 or 104 of their respective stepped disks. This construction insures the printing of the correct time if a printing is made just after the minutes disk has passed from 59 to zero, otherwise if the arms 99 and 100 of the plunger slides 82 and 83 were not clear of the points 102 and 103 or 104 of their respective stepped disks, the printing would or might indicate one hour less than the correct time.

From this description it will be seen that the object before stated, viz., to cause the printing type-wheels of higher orders to be set unerringly from the graduated elements having very slow movement, will be certainly attained during nearly all of the hour, arm 94 is gradually rocked by cam 92, thereby causing the plunger arms 99 to follow along with the graduated elements and in their planes of movement, while at the end of the hour, the high point of the cam 92 passes over in front of arm 94, thereby permitting an instant movement of arm 94 and pin 97 so that plunger arms 99 are returned

to their first position in which they are positioned to engage the succeeding step of the graduated elements.

Fig. 7 shows how the various plunger slides 80, 81, 82 and 83 are connected to their respective type-wheels. The plunger slides are connected through the intermediate pinions 67 to the rack slides 87 which in turn mesh with the pinions 88 which are sleeved to the type-wheels 89, the minutes plunger slide 80 being connected to the minutes type-wheel 105, tens of minutes plunger slide 81 to its respective type-wheel 106, and the hours plunger slide 82 to the type-wheel 107, the meridian plunger slide 83 to the type-wheel 108.

The operation of the device is as follows: The type-wheels which are under the control of the keyboard of the cash register are indicated at 110, 111, 112, 113, 114 and 115 (Fig. 1) and the pinions to which they are sleeved are shown at 116. Mechanism for rotating the pinions 116 is omitted from the drawings but the same operates to set the amount type-wheels simultaneously with the setting of the type-wheels which are under the control of the clock. The main drive shaft 78 is rotated twice during each operation of the machine. This causes a half revolution of the box cam 74 which in turn rocks the bell-crank lever 70 upwardly and then returns the same. When the bell-crank lever 70 is rocked upwardly the plunger slides 80, 81, 82 and 83 are also carried upwardly, through the pinions 67 which are hung from the bell-crank lever 70, until the slides are stopped by their respective stepped disks. Further movement of the bell-crank lever 70 to the end of its full stroke causes the pinions 67 to roll upon the plunger slides an amount which is inversely proportional to the extent of movement of the plunger slides before the same are stopped by their respective disks, and lift the rack slides 87 distances which are in correspondence with the rotation of their respective pinions 67 which rack slides 87 thereby cause rotation of the type-wheels an extent which is determined by the particular stops of the stepped disks which are in position to be engaged by the plunger slides. At this point the platen 119 and the platen 120 are moved against the opposite faces of the type-wheels and so cause impressions to be made upon the paper strips 117 and 118. (Fig. 2.) The impressions upon the two strips will be duplicates, as two like sets of type are carried by each of the type-wheels. Further rotation of the cam 74 will return the bell-crank lever 70 to its initial position and thereby return the various plungers and the type-wheels to their initial positions.

From the foregoing complete description, it will be evident that the mechanism is well adapted to attain the objects stated. The

clock is practically free from the necessity of doing external work and thereby will maintain a high degree of accuracy. Any type of time controlled device may be employed to perform this function of controlling the printing of the time and the invention is not to be limited to what are ordinarily termed "clock mechanisms." Any device which is time controlled and serves to permit the periodic actuation of the graduated elements, is considered to be within the invention. The graduated elements are shown as driven by a spring, but this is only one of many forms of driving mechanisms having potential energy stored therein and no other requisite for this mechanism is needed, broadly speaking, than to be constantly tending to drive the graduated elements and to be so controlled that it may be periodically permitted to actuate them. The printing elements may take many other forms and in fact, need not to be used to print at all, inasmuch as it is clearly possible to view the wheels, the device then serving as a time indicator, and such time indicator is a differentially movable element and may be positioned in many ways, though the mechanism herein shown in which gears 65 are given an invariable reciprocation in the planes of their rotation is highly satisfactory in practice. The partial gears 84 and 85 serve to change the invariable reciprocation of the driving devices into a differential movement of the time printer or time indicator.

The mechanism for manually adjusting the graduated elements when necessary is simply providing as it does, a mere connection herein shown as a ratchet and pawl, such that the graduated elements are normally driven by the escapement but may be manually given an additional movement.

While the form of mechanism herein shown and described is admirably adapted to fulfil the objects primarily stated, it is to be understood that it is not intended to confine the invention to the one form of embodiment herein disclosed, for it is susceptible of embodiment in various forms all coming within the scope of the claims which follow.

What is claimed is as follows:—

1. In a machine of the class described, the combination with printing mechanism including type-carriers, of graduated elements, connections for differentially adjusting said type-carriers by contact with said graduated elements, means having potential energy for driving said graduated elements, and devices adjusted in correspondence with one of said graduated elements for shifting the point of contact of one of said connections with another of said graduated elements.

2. In an accounting machine, the combination with printing mechanism of a

- type-carrier, a stepped cam, means for rotating the cam, clock mechanism controlling said means, a gear, means whereby the gear is given an invariable reciprocation radially to its axis upon each operation of the machine, a pair of racks meshing with the gear at opposite sides of the gear, one of said racks being mounted in alinement with the stepped cam so that the position of the cam determines the throw of the rack, the other of said racks having connections to alter the position of the type-carrier according to the movement of said rack when the machine is operated.
3. In an accounting machine, the combination with printing mechanism of a clock mechanism, a type-carrier, a stop, means controlled by the clock mechanism for setting the stop to different positions, a gear, means whereby the gear is given an invariable reciprocation radially to its axis upon each operation of the machine, a rack which meshes with said gear, a second rack which meshes with the opposite side of the gear, said first rack being mounted in alinement with the stop so as to be projected against said stop upon the reciprocation of said gear and cause rotation of said gear according to the distance of the gear from the end of its stroke upon the contact between the rack and stop, and connections whereby said second rack positions the type-carrier according to the rotation of said gear.
4. In a device of the class described, the combination with clock mechanism of a circular stepped plate, and connections for rotating said plate at a rate determined by the clock mechanism, a plunger, a type-carrier, means for positioning the type-carrier by moving the plunger into engagement with a step of the plate, the particular step which is opposite the plunger determining the extent of movement of the type-carrier, means controlled by the clock mechanism but independent of the rotation of the stepped plate for causing the plunger to be moved from the position for engaging one step, to a position for engaging another step.
5. In a device of the class described, the combination with clock mechanism of a circular stepped plate, with connections for rotating said plate at a rate determined by the clock mechanism, a plunger, a type-carrier, means for positioning the type-carrier by moving the plunger into engagement with a step of the plate, the particular step which is opposite the plunger determining the extent of movement of the type-carrier, and means for causing the plunger to engage a desired step of the stepped plate regardless of the rotation of the plate.
6. In a device of the class described, the combination with clock mechanism of a circular stepped plate, said plate being arranged to rotate at a rate determined by

the clock mechanism, a plunger, a type-carrier, means for positioning the type-carrier by moving the plunger into engagement with a step of the plate, the particular step which is opposite the plunger determining the extent of movement of the type-carrier, and means controlled by the clock mechanism for causing the plunger to engage a desired step of the stepped plate regardless of the rotation of the plate.

7. In an accounting machine, the combination with a pair of stepped plates, a plunger for each of said plates, means for moving the plungers into engagement with the stepped plates, type, means for positioning the type by the movement of the plungers, clock mechanism, means whereby the clock mechanism causes one of said stepped plates to move one step at regular intervals of time, and means under the control of said plate for causing the plunger for the other of said stepped plates to be moved at certain intervals into position for engaging a different step on its respective stepped plate.

8. In an accounting machine, the combination with a stepped plate of a plunger, means for moving the plunger into engagement with the stepped plate, type, means for positioning the type by the movement of the plunger, clock mechanism, and means controlled by the clock mechanism for moving said plunger to a position for engaging a different step of the stepped plate at certain intervals of time.

9. In an accounting machine, the combination with printing mechanism of a type-carrier, a movable stepped member, clock mechanism controlling the movement of the stepped member, a gear, means whereby the gear is given an invariable reciprocation radially to its axis upon each operation of the machine, and a pair of racks meshing with the gear at opposite sides of the gear, one of said racks being mounted in alinement with the stepped member so that the position of the member determines the throw of the rack, and the other of said racks having connections to alter the position of the type-carrier according to the movement of said rack when the machine is operated.

10. In an accounting machine, the combination with printing mechanism of a type-carrier, a movable stepped member, clock mechanism controlling the movement of the stepped member, a gear means whereby the gear is given an invariable reciprocation radially to its axis upon each operation of the machine, a pair of racks meshing with the gear at opposite sides of the gear, one of said racks being mounted in alinement with the stepped member so that the position of the member determines the throw of the rack, the other of said racks having connections to alter the position of the type-car-

- 3
- rier according to the movement of said rack when the machine is operated, and means for causing the plunger rack to engage a certain step of the stepped member regarding the movement of the stepped member.
11. In a machine of the class described, the combination with printing mechanism including type-carriers, of graduated elements, connections for differentially adjusting said type-carriers by contact with said graduated elements, means for periodically driving said graduated elements, and an arm moved in correspondence with a graduated element of lower order and controlling the point of contact of one of said connections with a graduated element of higher order.
12. In a machine of the class described, the combination with printing mechanism including type-carriers, of graduated elements, connections for differentially adjusting said type-carriers including plungers positioned to engage said graduated elements, means for periodically shifting said graduated elements, and an arm moved in correspondence with a graduated element of lower order and constructed to shift one of said plungers in the plane of movement of a graduated element of higher order.
13. In a machine of the class described, the combination with a periodically movable element, and means possessing potential energy normally tending to move said element, including a driving wheel and an escapement device; a connecting device mounted on said movable element and normally engaging said driving wheel to be driven thereby, and manipulative means for additionally moving said periodic element and said connecting device.
14. In a machine of the class described, the combination with printing mechanism including type-carriers, of graduated elements, means for differentially adjusting said type-carriers by contact with said graduated elements, and devices adjusted in correspondence with one of said graduated elements for shifting the point of contact of certain of said adjusting means with others of said graduated elements.
15. In a machine of the class described,
- the combination with printing devices including type-carriers, of means for differentially adjusting said carriers and then returning them to normal position, stepped elements with which said adjusting means are positioned to engage and be obstructed, and devices adjusted in correspondence with one of said stepped elements for shifting the point of engagement of certain of said adjusting means with others of said stepped elements.
16. In a machine of the class described, the combination with printing devices including a type-carrier, of means for differentially adjusting said carrier, a stepped element with which said adjusting means is positioned to engage and be obstructed, and means for periodically shifting the position of a part of said adjusting means to shift the point of said engagement.
17. In a machine of the class described, the combination with a printing device including a type carrier, of a gear mechanism comprising two partial gears of different radii, a driving rack for said printing device engaging one of said partial gears, a second rack engaging the other of said partial gears, a graduated element for obstructing said second rack, and a clock mechanism controlling said graduated element.
18. In a machine of the class described, the combination with a differentially movable element, of a gear mechanism comprising two partial gears of different radii, means for giving said gear mechanism an invariable reciprocation in the plane of its rotation, a driving rack for said differentially movable element engaging one of said partial gears, a second rack engaging the other of said partial gears, means for obstructing said second rack at different points, and a clock mechanism controlling said obstructing means.
